(57) **CLAIM**

The ornamental design for a dual roll desktop tape dispenser, as shown and described.

DESCRIPTION

FIG. 1 is a perspective view showing the new design for a dual roll desktop tape dispenser.

FIG. 2 is a right side view showing the new design for a dual roll desktop tape dispenser.

FIG. 3 is a top view showing the new design for a dual roll desktop tape dispenser.

FIG. 4 is a front view showing the new design for a dual roll desktop tape dispenser

FIG. 5 is a bottom view showing the new design for a dual roll desktop tape dispenser; and,

FIG. 6 is a back view showing the new design for a dual roll desktop tape dispenser.

The structure depicted by means of broken lines in the figures has been shown for illustrative purposes only and forms no part of the claimed invention.
